CARL J. FRISK AND EMIL OKERGREN, OF SAN FRANCISCO, CALIFORNIA.

DOUBLE-UP UMBRELLA.

1,117,365.

Specification of Letters Patent. Patented Nov. 17, 1914.

Application filed February 11, 1914. Serial No. 817,981.

To all whom it may concern:

Be it known that we, CARL J. FRISK and EMIL OKERGREN, a citizen of the United States and a subject of the King of Sweden, 5 respectively, residing at San Francisco, in the county of San Francisco and State of California, have invented new and useful Improvements in Double-Up Umbrellas, of which the following is a specification.

10 The object of the present invention is to provide an umbrella which can be quickly and conveniently reduced in length so as to enable it to be inserted in a valise, traveling bag, or other receptacle of comparatively 15 small length, for the purpose of traveling or storage, and which can also be quickly and conveniently extended for use.

In the accompanying drawing, Figure 1 is a broken sectional view of the umbrella 20 open, the stick being shown in side elevation and many of the ribs being omitted for the sake of clearness; Fig. 2 is a similar view of the upper portion of the umbrella folded into a small compass; Fig. 3 is a 25 sectional view on an enlarged scale of the middle portion of the stick; Fig. 4 is an enlarged longitudinal sectional view of a latching device; Fig. 5 is a cross-sectional view of the same; Fig. 6 is an enlarged side 30 view of a rib pivot; Fig. 7 is a plan view of the same.

Referring to the drawing, 1 indicates the stick of the umbrella, which is in the form of a metal tube made of separable sections 35 2, 3 and 4. The middle section 3 is formed with reduced tubular ends, which fit snugly within the adjacent ends of the sections 2 and 4, and in order to connect said sections with each other there is pivoted at 6 in the 40 section 3, a spring 7 having a humped portion 8 extending through a narrow longitudinal slot 9 in the section 3 and adapted to be repressed by the thumb to operate the spring. Said spring has its ends bent outwardly to form catches 11 and 12, extending through holes in the reduced terminal portions of the middle section 3, and adapted to extend through holes 13, 14, correspondingly located in the adjacent ends of the 45 tube sections 2 and 4. Said catches 11, 12, are shaped to provide beveled outer surfaces, as shown at 16, 17, so that when the ends of the section 3 are properly inserted in those of the sections 2 and 4 they lock 50 automatically. By pressing in the humped portion of the spring, said catches can be

withdrawn from said holes 13, 14, and the tube sections 2, 3 and 4 can be separated from one another.

Upon the tube section 4 is fixedly secured 60 a ring 18, to which inner rib sections 19 are pivotally attached in the manner in which ribs are at present attached to such rings on an ordinary umbrella. To the outer ends of these rib sections are secured tubes 21 which 65 at their outer ends terminate in forks 22, between which are received the collapsed sides of terminal portions of tubes 23, surrounding the adjacent ends of outer rib sections 24. The forked outer end of each tube 21 is 70 contained between the forked outer end of a stay 26, and through small registering holes in the outer ends of the stay 26 and the tubes 23 and 21 passes a pivot pin 27, by which means both the rib sections 19, 24 are 75 pivotally secured to the stay 26 and to each other. The inner ends of these stays 26 are pivotally attached in the usual manner to a slide ring 28 slidable upon the umbrella stick. 80

Around the outer rib sections, and attached thereto at a short distance from their pivotal attachments to the inner rib sections, are secured tubes 29 having inward extensions which pass between, and are pivotally 85 secured, as shown at 31, to forks 32, secured upon the outer ends of stretchers 33, the inner ends of which are pivotally secured in the usual manner to a runner 34, slidable upon the stick independently of the slide 90 ring 28. Secured to said runner 34 is a tube 36, having therein a longitudinal slot 37 adapted to register, in the closed position of the umbrella, with a slot 38 in the stick, and in the open position with a slot 39 95 therein. Through said slot 37 a catch 41 extends inwardly from a sleeve 42 surrounding the tube 36 and contained between a shoulder 43 on said tube 36 and a tube 44 around the tube 36, said tube 44 being 100 pressed downwardly by a coiled spring 46 compressed between the tube 44 and a shoulder 47 on the tube 36. The tube 44 has a downwardly extending sloping or wedge-shaped portion 48, which can be engaged by 105 a similarly shaped or sloping portion 49 of the sleeve 42. When said sleeve 42 is pressed inward by pressure applied to an extended portion 51 at the side thereof opposite to the catch 41, said sloping portion 49 engages the sloping portion 48 of the tube 44, and presses said tube 44 upward, 110

compressing the coiled spring 46. When pressure is released from the sleeve 42, the force of the compressed spring causes the sloping portion of the tube 44 to abut 5 against the sloping portion of the sleeve 42 and restores said sleeve 42 to its normal position, in which the catch 41 extends inwardly through the slot 37 and also through the slot 39 or 38, as the case may be, 10 thus holding it in either the open or closed position as desired. A tubular casing 52 surrounds the tube 36 and has a hole on one side into which the extended side of the sleeve 42 fits snugly and closes it. The 15 cover 50 of the umbrella is attached to the upper fixed ring 18, to the outer ends of the outer rib sections 24, and also to the outer rib sections at points intermediate between the tubes 23 and 29.

20 The umbrella is opened in the usual manner by applying the first finger and thumb to the casing 52 and pushing upwardly thereon, the ribs of the umbrella opening out in the same manner as those of an ordinary umbrella. The slide ring 28 and runner 34 then travel upward at a substantially uniform distance from each other, until the slide ring 28 arrives at the upper catch 12, when said slide ring 28 is arrested thereby.

25 The runner 34 can, however, be still pushed upwardly, until it comes substantially in contact with the slide ring 28, in which position the inwardly extending catch 41 springs inwardly into the upper slot 39. By 30 the final upward movement of the runner 34 into contact with the slide ring 28 the rib sections are straightened out as much as is permitted by the cover 50 of the umbrella. To close the umbrella, the thumb is applied 35 to the extended portion 51 of the sleeve 42 to withdraw the catch 41 from the slot 39, and the tube 36 is withdrawn in the usual manner, the catch 41 entering the lower slot 38 to hold it in its closed position.

40 To bring the umbrella to a compact form suitable for packing for transportation or storage, the outer ends of the outer rib sections are encircled by the hand, and at the same time pressure is applied to the sleeve 42 to release the tube 36, and said tube 36 and the runner 34 are pushed upwardly. By reason of the outer rib sections being held down in the position in which they are almost parallel with the stretchers 33, the 45 runner 34 moves along the stick at a much greater distance from the slide ring 28 than when opening the umbrella for use as before explained. Consequently when the slide ring 28 arrives at the upper catch 12, the runner 34 has also arrived at the humped portion of the spring, as shown in dotted lines, and has repressed the same within the tube section 3. This movement of the 50 spring, caused by the movement of the humped portion into the tube section 3,

causes the catch 12 to be withdrawn, but not far enough to disconnect the tube sections, so that the slide ring 28 passes said catch 12 and can move into close proximity with the fixed ring 18. The upper portion of the 70 runner 34 is formed in its inner side with a recess or cup 54 which can receive the upper catch 12 when it arrives thereat. In this position all the inner and outer rib sections and stays and stretchers are collapsed very 75 closely around the upper tube section. The tube sections can now be detached from each other by pressing inwardly the hump-shaped portion of the spring and drawing the outer tube sections 2, 4 from the middle 80 tube section 3. The tube sections 3 and 2, the latter supporting at its outer end the usual handle 55, are made of substantially the same length as the combined length of the upper stay section and the rib section 85 when in the closed position just described, so that the total length of an umbrella of ordinary size, when it is taken to pieces, need not be more than about fourteen inches, and can thus be packed or stored in a comparatively small compass, and may be carried in the coat pocket without its being too conspicuous.

There are many important advantages 90 possessed by a foldable umbrella of the above described construction. First, by reason of the umbrella ribs folding inward, the umbrella can be folded all at once, whereas with foldable umbrellas in which the ribs fold outward, much time is occupied in arranging the cover around the ribs, and in fact it is extremely difficult in windy weather to fold the umbrella at all. This capability of the ribs folding inwardly is produced by our improved method of using 95 stays and stretchers, and pivoting the two sections of the ribs together. It will be observed that the pivot of each rib is slightly, about one-sixteenth of an inch, beneath or within the inner edges of the ribs. In reducing the umbrella to a compact form 100 for the purpose of transportation or otherwise, the ribs and cover automatically assume their proper positions by the mere pushing upward of the tube 36, and all that is necessary is to detach the stick sections from each other, which is easily done, requiring only the pressure of the thumb upon the humped portion of the spring and the drawing out of the terminal sections from the middle section. Such operation evidently requires no skill or experience to perform. Furthermore, the construction is such that when the rib sections are folded on one another the cover of the umbrella is folded so 110 as to fit very snugly and tightly around said ribs, and leave no loose parts which have to be separately arranged in position. This is due to the cover being on the outside of the ribs when folded together, and to the 115 120 125 130

positions of the pivots, which cause the rib sections to fold on one another at exactly the right point to cause the cover to fit tightly, yet not too tightly thereover. A 5 further advantage is that both the inner and outer rib sections are each attached at two points to rigid material, the inner rib sections to the fixed ring and to the stays and the outer rib sections to both the stays and 10 stretchers. Consequently both rib sections are under full control and do not require to be operated by hand in order to change the condition of the umbrella.

We claim:—

15 1. An umbrella having a tubular stick, inner and outer rib sections, stays pivoted to the inner rib sections, stretchers pivoted to the outer rib sections, a slide ring pivoted to the stays, a runner pivoted to the 20 stretchers, a spring having a catch projecting through a hole in the tubular stick, and having a protuberance extending through a slot in the tubular stick, the lengths and arrangement of said rib sections, stays and stretchers being such that, 25 in the upward movement of the runner to

open the umbrella, the runner engages said protuberance to withdraw the catch when the slide ring arrives thereat to permit said slide ring to pass thereover. 30

2. An umbrella having a tubular stick, inner and outer rib sections, stays pivoted to the inner sections, stretchers pivoted to the outer sections, a slide ring pivoted to the stays, a runner pivoted to the stretchers, 35 means projecting through an upper hole in the tubular stick for arresting the slide ring in its upward movement, and means projecting through a lower hole in the stick and operatively connected with the first- 40 named means to withdraw the latter with the withdrawal of the former, the outer rib sections being secured to the stretchers at a distance from the pivots of the rib sections.

In testimony whereof we have hereunto 45 set our hands in the presence of two subscribing witnesses.
